UNITED STATES PATENT OFFICE.

CHARLES B. KIRKHAM, OF BUFFALO, NEW YORK, ASSIGNOR TO CURTISS AEROPLANE AND MOTOR CORPORATION, A CORPORATION OF NEW YORK.

MAGNETO GEARING.

1,423,334.

Specification of Letters Patent.

Patented July 18, 1922.

Original application filed May 18, 1916, Serial No. 98,336. Divided and this application filed August 10, 1917. Serial No. 185,517.

To all whom it may concern:

Be it known that I, CHARLES B. KIRKHAM, a citizen of the United States, residing at Buffalo, in the county of Erie and State of New York, have invented certain new and useful Improvements in Magneto Gearing, of which the following is a specification.

My invention relates to magneto drives and more particularly to the provision of a reversing means therefor.

This application is a division of a copending application, Serial No. 98,336, filed May 18, 1916, now Patent 1,351,763, Sept. 7, 1920, for an aeronautical motor. The aeronautical motor in connection with which my invention is utilized is of such construction that by simply reversing the cam shaft and with a few other minor adjustments the operation of the motor as a whole is reversed whereby it may be used to serve as a clockwise or anti-clockwise motor as desired. It is evident, however, that if the direction of rotation of the motor proper is reversed it is necessary that some reversing mechanism be interpolated between the magnetos and their drive shaft since the magnetos are constructed for operation in one direction only. This reversal of the drive for the magnetos is accomplished very simply and effectively in my invention by means of a single element in the form of a bevel gear which is carried upon the drive shaft and is adapted to engage bevel gears carried by each of the magnetos. It will be noticed that the particular motor in connection with which my invention is illustrated is equipped with two magnetos although it is equally adaptable for usage with one or more magnetos as the demands of the ignition system shall require.

In the event that two magnetos are used they are symmetrically disposed with reference to a common magneto drive shaft which carries the above mentioned bevel gear. When this bevel gear is disposed in one definite relation to the gears carried by the respective magnetos a certain definite relation between the directions of rotation of the shaft and magnetos is produced. By simply reversing the single gear upon the common drive shaft, however, the relative directions of rotation are reversed.

Of the drawings:

Fig. 1 is an end view of the motor showing the magnetos in side elevation; 55

Fig. 2 is a partial sectional view showing the disposition of the driving means with respect to the motor;

Fig. 3 is a detail sectional view of the driving means. 60

In Fig. 1, two magnetos 10 are shown supported upon the brackets 11 which are formed upon the crank case (not shown) of the motor. With reference to the longitudinal axis of the motor the magnetos 10 are 65 preferably symmetrically located in order that they may both be driven from the crank shaft 12 by means of the gears 13 and 14 which serve to operate the magneto drive shaft 15 which is located directly above the 70 crank shaft. The drive shaft 15 is supported at its extremities by means of ball bearings 16 and 17 as shown in Fig. 2. Each of the magnetos 10 has its shaft 18 equipped with a bevel gear 19. The drive shaft 15 75 also is equipped with an adjustable bevel gear 20 which is adapted to commonly engage the two bevel gears 19 carried by the magneto shafts.

Referring to Fig. 3 it may be noticed that 80 the gear 20 is secured to the shaft 15 by means of a pin 21 whereby upon releasing the pin the gear may be slipped loosely along the shaft. It may also be seen that the construction of the gear and the location 85 of the pin 21 relative to the gear and the shaft is such that it may be placed upon the shaft in either of two positions as shown by the dotted lines at 22 whereby the relative direction of rotation of the drive shafts 15 90 and the magneto shafts 18 may easily be reversed at will.

The entire magneto drive mechanism is enclosed within a housing 23 which is integrally formed upon the crank case casting. 95 The housing 23 is provided as shown in Fig. 2 with a removable end cap 24 which carries secured within it the ball bearing 17 which supports the outer extremity of the drive shaft 15. At each side the housing 23 100 is also provided with the removable bearings and retaining caps 25 as shown in Fig. 1.

The operation of my invention is as follows:

Suppose it is desired to reverse the direction of rotation of the magnetos relative to that of the drive shaft 15. The magnetos may very quickly be loosened from their 5 mountings whereby they may be slipped to the right and left thereby partially withdrawing the gears 19 and their supporting bearings and caps 25 from the housing 23 in order to provide suitable clearance for subsequently withdrawing the gear 20. The cap 24 which is held by means of the bolts 26 is next removed carrying with it the bearing 17 whereby access may be had to the interior of the housing permitting the pin 21 10 to be driven out and the gear 20 withdrawn through the opening. The gear 20 may then be slipped on in its reverse position and the pin driven through it to secure it to the shaft whereupon the cap and bearing may 15 be replaced and the magnetos returned to their original positions so that their gears 19 are in contact with the gear 20.

Although I have described more or less specific details in setting forth my invention, it is to be understood that interpretation thereof is to be made only in the light of its generic spirit and of the subjoined 20 claims.

What is claimed is:

- 30 1. In a internal combustion engine, the combination of a crank shaft capable of being driven in a reverse direction, an engine frame within which the crank shaft is mounted, a megneto mounted directly upon the engine frame at one end thereof, and a driving connection between the crank shaft and the magneto including a shaft journaled in the engine frame and geared to the crank shaft, said shaft being provided with a slideable and reversible gear whereby through a change in the relative position of the gear on the shaft the magneto may be operated in the same direction even though the direction of rotation of the crank shaft 40 be reversed.
2. In an internal combustion engine, the combination of a crankshaft, an engine frame, a shaft geared to the crankshaft, engine accessories carried by the engine frame 45 respectively on opposite sides of the last mentioned shaft, a bevel gear carried by the last mentioned shaft, said gear and said

shaft being enclosed within the engine frame, separate shafts for the engine accessories, and separate bevel gears for the separate shafts likewise enclosed within the engine frame, both bevel gears being in mesh with the bevel gear first mentioned. 55

3. In an internal combustion engine of the reversible type comprising an engine frame, a crank shaft capable of being driven in a reverse direction, dual opposed magnetos mounted upon one end of the engine frame and a driving connection between said shaft and said magnetos comprising a single reversible element incorporated therein to provide for the operation of the magnetos in the same direction upon the reversal of rotation of the shaft. 60

4. In an internal combustion engine of the reversible type comprising an engine frame, a crank shaft therein capable of being driven in a reverse direction, a drive shaft carried by one end of the engine frame and driven from said crank shaft, dual magnetos located symmetrically with respect to said drive shaft, a driving gear of the bevel type carried by each of said magnetos and a beveled gear slidably and reversibly mounted upon said drive shaft whereby the 70 relative direction of the rotation of the drive shaft and the magnetos may be changed. 75

5. In an internal combustion engine, a drive shaft, dual magnetos located symmetrically with respect to said shaft, a gear 80 carried by each of said magnetos, and a gear adjustably attached to said shaft so that the relative direction of rotation of the shaft and the magnetos may be changed. 85

6. In an internal combustion engine, a drive shaft, a pair of magnetos axially aligned but disposed on opposite sides of said drive shaft, a bevel gear carried by each of said magnetos and a bevel gear slidably and reversibly attached to said shaft and 90 acting as a driving connection between said shaft and said magnetos whereby relative direction of rotation of the shaft and the magnetos may be effected for the purpose set forth. 95

In testimony whereof I hereunto affix my signature.

CHARLES B. KIRKHAM.
